UNITED STATES PATENT OFFICE.

DAVID W. CASSEDAY, OF MINNEAPOLIS, MINNESOTA.

DESIGN FOR A BADGE.

SPECIFICATION forming part of Design No. 26,145, dated October 6, 1896.

Application filed June 18, 1896. Serial No. 596,077. Term of patent 7 years.

To all whom it may concern:

Be it known that I, DAVID W. CASSEDAY, a citizen of the United States, residing in the city of Minneapolis, county of Hennepin, and State of Minnesota, have invented and produced a new and original Design for Badges, of which the following is a specification, reference being had to the accompanying drawings, showing the same.

10 In the drawings, Figure 1 is a face view of the badge; Fig. 2, a side or edge view of the same, which views are deemed sufficient to illustrate the design.

15 The leading feature of my design consists in the representation of the head of an elephant on a disk.

In the drawings, 1 designates the disk or base of a badge; 2, a representation of the head of an elephant thereon; 3, a shank at-

tached to the disk, and 4 a button on the 20 shank.

The primary object of the design being its use in connection with a campaign-badge, it is preferable that the elephant's head be of gold color and the disk or base black or of some 25 distinctive color, in order to display the characteristic feature more prominently; but the coloring is not deemed essential to the invention.

What I claim is—

30 The design for a badge, substantially as herein shown and described.

In testimony whereof I have hereunto set my hand this 16th day of June, 1896.

DAVID W. CASSEDAY.

In the presence of—

R. BLUME,
P. H. GUNCKEL.
